UNITED STATES PATENT OFFICE.

JOHN KOSTER, OF SAN FRANCISCO, CALIFORNIA.

DESIGN FOR A PICTURE EASEL OR THE LIKE.

Application filed November 3, 1927. Serial No. 23,991. Term of patent 3½ years.

To all whom it may concern:

Be it known that I, JOHN KOSTER, a citizen of Germany, residing at San Francisco, in the county of San Francisco and State of California, have invented a new, original, and ornamental Design for Picture Easel or the like, of which the following is a specification, reference being had to the accompanying drawing, forming part thereof.

new design, it being understood that the other two sides are substantially the same as the one shown.

I claim:

The ornamental design for a picture-easel or the like, substantially as shown and described.

JOHN KOSTER.
